ABSTRACT

In a deflector for an abrasive-accelerator in a blasting machine, comprising a hollow tubular body having at one end a central opening for receiving an impeller of the accelerator, with the other end being detachably attached to a chute section of the accelerator, and a slot formed locally through the circumferential wall of the body for hurling particles of abrasive therethrough towards the rotating vanes surrounding the rotating impeller, the slot having a parallelogram configuration and being inclined relative to the central longitudinal axis of the deflector body, said inclined slot being of a circumferential width such that the angle formed by the radial outermost end edges of the parallelogram relative to the longitudinal central axis of the body corresponds to the angle through which the particles are blasted by the vanes onto the surface of a work-piece and that the overall axial length of this parallelogram is not greater than the breadth of the vane. Such a deflector is able to blast abrasive particles with uniform density onto the work surface and can increase the effective working length of blasted particles received by the surface and also can reduce the time required for the processing of the surface.

PRIOR ART

DEFLECTOR FOR ABRASIVE-ACCELERATOR IN BLASTING MACHINE

BACKGROUND OF THE INVENTION

1. Field of the Invention

The present invention is concerned with a deflector for an abrasive-accelerator in a blasting machine, and more particularly it pertains to an improvement in such a deflector.

2. Description of the Prior Art

A known abrasive particles accelerator comprises, as shown in FIGS. 6 and 7, a base frame 1, casing 2 fixed to his base frame 1, a chute 3, a deflector 4 attached to said chute 3, and a disk 5 provided concentrically with said deflector 4. The disk 5 is rotated via a pulley 8 and a shaft 9. On one flat surface of this disk 5 are attached a plurality of vanes 6 radially of the disk. In the central opening of the disk 5 is positioned an impeller 7 which is fixed to the shaft 9. A slot 10 is formed locally through the circumferential wall of the deflector 4 so as to face the vane 6 so that particles of abrasive may be hurled therethrough toward the surfaces of the vanes 6. The slot 10 is either square or rectangular in configuration when viewed from directly thereabove as shown in FIG. 8 so that its opposing two edges 10a and 10a are parallel with the central longitudinal axis C or with the central rotating axis of the impeller and the vanes, and also that the opposing other two edges 10b and 10b of this slot 10 are perpendicular to said central longitudinal axis or to said opposing two edges 10a and 10a and are parallel relative to each other. The length a of each edge 10a of one pair is not greater than the breadth W of the vane 6. The length b of each edge 10b of the other pair is equal to the arc formed on the circumferential wall of the deflector with an angle α extending from the center of a circle and corresponding substantially to the angle β through which particles of abrasive are blasted by the vanes 6. The particles of abrasive which are discharged through the slot 10 are then blasted onto the surface of the workpiece 11 through a blasting angle β which is substantially equal to said center angle α , so that the surface of the workpiece 11 is processed through the range of area defined by the breadth d and the length L as shown in the drawing.

As indicated by the broken lines in FIG. 7, the density of the particles of abrasive at the surface of the workpiece 11 is such that the profile of the density of the blasted particles of abrasive takes a sort of angular configuration, in which this angular profile for the entire length L of blast shows a progressive downward inclination on both sides of this angular profile. As will be understood from the drawing, the length L' covered by those blasted particles located in that portion having a density sufficient for being useful in processing said surface of the workpiece is seen to be considerably small as compared with the overall length L of the blasted particles. Accordingly, the amount of the abrasive particles serves to be quite critical in processing so that in case the amount discharged is smaller than the optimum rate of blast, the length L' of the useful particles of blast will become very small. Contrariwise, in the event that the rate of blast is greater than the optimum rate, the length L' will become closer to the length L , but the numerous streams m of the bouncing particles which occur after they run into the surface of

the workpiece as they are blasted from the vanes will obstruct the paths of the particles being blasted from the vanes and thus they interfere with these fresh particles coming from the vanes, causing unevenness in the processing of the surface. In order to solve these problems, it is considered that the area of opening of the hurling slot may be reduced. However, in view of the fact, as stated above, that the length b of the opposing edges of the slot governs the angle β of the blast of the accelerator, it is impossible to reduce this length. On the other hand, the length a of the opposing other edges of the slot is determined as a matter of course relative to the breadth W of the vane in view of the wear of the vane. If this length a is reduced beyond the optimum length, the vane will locally become worn out quickly.

SUMMARY OF THE INVENTION

It is, therefore, the primary object of the present invention to provide a deflector having a slot of an improved configuration for hurling particles therethrough to make it possible that, irrespective of the flow rate of the abrasive particles blasted, these particles impinging onto the surface of the workpiece will have a uniform density throughout the entire length of the blast received on the surface of the workpiece, and that the distance through which the work surface is processed by the blasted particles is prolonged, and that this processing requires a much reduced length of time as compared with the prior art without causing any uneven result of processing.

BRIEF DESCRIPTION OF THE DRAWINGS

FIG. 1 is a perspective view showing a preferred example of the deflector according to the present invention.

FIG. 2 is a side view of the same deflector shown in FIG. 1.

FIG. 3 is a side view showing another preferred example of the deflector embodying the present invention.

FIG. 4 is a side view showing still another preferred example of the deflector embodying the present invention.

FIG. 5 is a perspective view in an exploded fashion of the deflector shown in FIG. 4.

FIGS. 6 through 7 show the structure and function of a known abrasive-accelerator of a blasting machine, in which:

FIG. 6 is a vertical sectional view of the abrasive-accelerator; and

FIG. 7 is a sectional view, taken along the line VII-VII in FIG. 6, of the deflector, vanes and impeller.

FIG. 8 is a side view of a known deflector used in the abrasive-accelerator shown in FIGS. 6 and 7.

DETAILED DESCRIPTION OF THE PREFERRED EMBODIMENTS

In order to satisfy the aforesaid object, the deflector according to the present invention is provided with a slot having a parallelogram configuration for hurling abrasive particles therethrough to the vanes. This slot opens through the circumferential wall of the deflector with an inclination relative to the central longitudinal axis of the deflector. Moreover, this slot is such that its width between the opposing two outermost edges positioned radially of and possibly in parallel with the cen-

tral longitudinal axis of the deflector is determined by the angle of blast of the abrasive particles discharged from the vanes, and that the overall axial length of the slot is not larger than the breadth W of the vane. Such a slot enables the abrasive particles to be hurled out uniformly along the edges of opening of the slot which is inclined relative to the longitudinal central axis of the deflector. At the same time, the hurled particles of abrasive are restricted of the extension of their spread by these edges of opening. As a consequence, the abrasive particles are hurled onto the vane in uniform density with a length equal to the axial length of opposing two edges of opening and with a breadth equal to the breadth of the other opposing two edges of opening of the inclined parallelogram slot. Because of this arrangement, it is possible to blast abrasive particles onto the surface of the workpiece in uniform density throughout the desired end-to-end distance of blast, even when the rate of blast of the abrasive particles is substantially small. Also, because the area of opening of the slot through which the particles of abrasive are hurled out is small as compared with that of the deflector of the prior art, these abrasive particles are never discharged in an excessive amount, and this prevents the aforesaid undesirable phenomenon of interference between the bouncing particles and the fresh particles, thus keeping uneven blasting from taking place.

Referring now to the drawings, the examples of the deflector shown in FIGS. 1 through 3 are each constructed to be used in the apparatus shown in FIGS. 6 and 7. At one end of the hollow tubular body 15 is provided, integrally therewith, a plate 17 having an opening 16 for receiving an impeller 7. At the other end of this body 15 is mounted an attachment 18 so that the body 15 is detachably attached to a chute 3 by means of this attachment 18. A slot 12 is formed through the circumferential wall of the body 15 for hurling out abrasive particles supplied from the chute 3.

In the examples shown in FIGS. 1 and 2, the slot 12 is of a parallelogram configuration and opens through the wall of the body 15 with an inclination relative to the longitudinal central axis C of the deflector or to the central rotary axis of the impeller 7 or the vanes. Each of a pair of parallel edges 12b and 12b of opening of said slot 12 is formed in such a way that the length of this edge b corresponds to the line of arc defined on the circumferential wall of the body 15 with a center angle α of the opening — namely, with an angle α which is substantially equal to the angle β through which the abrasive particles are blasted from the vane. The other pair of edges 12a and 12a of opening which are parallel with each other are formed so that the distance a between these two edges 12a and 12a is of the following relation with respect to the breadth W of the vane 6: $a \leq W$. As a consequence the length of the edge 12b of the opening has the following relation with respect to the breadth W of the vane: $a \leq W$.

In the embodiment shown in FIG. 3, the slot 12 is of a parallelogram shape as in the preceding example. This slot opens through the circumferential wall of the body 15 with an inclination relative to the longitudinal central axis C of the deflector. However, it will be noted that the edges 12a and 12a of opening are arranged in a different fashion as compared with those shown in FIG. 2. More specifically, these two edges 12a and 12a are arranged so as to be parallel with the longitudinal central axis of the deflector. A deflector having

a slot of such a shape may present a slight unevenness in the density of the abrasive particles blasted from the vane, but still the blast is sufficiently useful in actual operation. In each of these examples, there is formed only a single slot in the body 15. If necessary, however, for example if it is intended to blast abrasive particles onto two separate workpieces, there may be provided another or a second slot formed through the circumferential wall of the body 15 at a position diametrically opposite to the first one.

In the deflector shown in FIGS. 4 and 5, the area of opening of the slot is arranged so that it can be varied freely. This body is comprised of two body sections, one of which is inserted in the other one of these two body sections. The first one of the two body sections 15A is of a hollow tubular shape and has at one end a flange 18 which is integral with the body section 15A and which is to be attached to the chute 3. The other or the second body section 15B into which said first body section 15A is to be rotatably inserted has also a hollow tubular shape and is provided at one end with a ring 19 for limiting the unnecessary axial movement of the body section 15A and at the other end with a plate 17 having an opening 16 for receiving an impeller 16. A slot 12 is arranged to be formed when the cutouts formed through the circumferential walls of these two body sections, respectively, are rendered to overlap each other as the second body section which receives or the first body section therein is rotated relative to the first one. Because of this arrangement, it should be noted that each of the pair of edges 12b and 12b of the openings of these two cut-outs is inclined relative to the longitudinal central axis C of the deflector, whereas the edges 12a and 12a of the other pair are perpendicular to said longitudinal central axis of the deflector. Moreover, the axial length a between the edges 12a and 12a is of the following relation with respect to the breadth W of the vane: $a \leq W$. On the other hand, the length b between the two outermost ends of the edges 12b and 12b is determined so as to be equal to the line of arc formed on the circumferential wall of the body to correspond to the angle of blast of the abrasive particles delivered from the vane.

In a deflector described above, it is possible to acquire an area of opening of the slot which meets the rate of flow of abrasive particles, without changing the conditions in which the abrasive particles are hurled onto the vane. The control of the area of opening of the slot can be effected, for example, by providing teeth or gear formation on the periphery of the ring 19 of the body section 15A so that this gear is rotated externally of the accelerator.

I claim:

1. A deflector for an abrasive-accelerator in a blasting machine which includes a rotatable impeller, means for conveying abrasive material to said impeller and a plurality of vanes for directing said abrasive material onto a workpiece, the improvement comprising a hollow tubular deflector body having one end open for receiving said impeller, said impeller being rotatably positioned within said deflector body, said deflector body having at least one slot formed through the circumferential wall thereof for permitting abrasive particles to be hurled out to said vanes of said accelerator through said slot, wherein said slot is of a parallelogram shape and forms an opening in said wall of said body with an inclination relative to the longitudinal central axis of the deflector and wherein two edges of the slot are arranged perpendicular to the longitudinal central axis of the deflector.
